AUTOMATIC IDLE COURSE MECHANISM FOR
STRAIGHT KNITTING MACHINES

Melchior Zwicky, Berkshire Heights, and Rudolph Anke, Ridge Park, Reading, Pa., assignors to Textile Machine Works, Wyomissing, Pa., a corporation of Pennsylvania

Application March 30, 1935, Serial No. 13,818

15 Claims. (Cl. 66—82)

Our invention relates to idle-course mechanisms for knitting machines, and particularly to means for preventing adverse effects, heretofore resulting from the running of idle courses.

5 During the production of hosiery, particularly on a full-fashioned knitting machine, it is necessary to periodically insert idle courses, which may be defined as the operations of the machine through a complete cycle, without adding loops to the fabric, and without pressing the loops of the next previously-knitted course from the needles. The introduction of idle courses is necessary, as during the return of yarn carriers to original positions, after knitting an odd number 10 of courses, or when the slurcocks are to be moved to the opposite side of the knitting section, without adding a course of loops to the fabric.

An example, of an operation where idle courses are effected, is when the ravelling course carrier is moved from an inoperative position 20 outside the selvedge edge of the fabric to a position along the edge of the ravelling course area. Two idle courses are necessary to effect this movement, one for couloring the ravelling course carrier from the right to the left side of the knitting field, and the other to return the couloring mechanism to the right side, as the other carriers remain idle at the right side of the knitting field.

Operating a full-fashioned knitting machine in 30 a usual manner, without feeding yarn thereto, for moving the slur cock boxes, etc., from one side of a knitting section to another, results in a press-off, and a break in the connection between the needles and the fabric.

35 A well-known mechanism, employed to effect idle courses, is shown and described in the assignee's Full-Fashioned Knitting Machine Catalogue, copyright 1929. This mechanism provides means to prevent closing the needle beards, by the presser edge, during the downward travel of the needles, and thus, although yarn may or may not be fed to the needles, no press-off occurs, since the loops of the next previous course, instead of being cast from the needles, are again 40 caught beneath the needle beards.

When certain yarn carriers are moved across the knitting field, without adding loops to the fabric, the above-mentioned prior art idle course 45 mechanism, although precluding fabric press-offs, permits loops to be formed about the needles, and to become sufficiently entangled therewith to create an undesirable condition, which must be corrected before the machine may be further operated for knitting.

The upward and downward movements of the needles, while the loops carried thereby are held between the knockover bits and the sinkers, tend to lengthen, and to produce undesirable wear on the loops, thus having an undesirable effect on 5 the finished product.

It is among the objects of our invention to avoid the above-mentioned objectionable features incident to the operation of idle courses, whereby the delay, expense and annoyance accompanying 10 the disentangling of yarns from the needles, the trouble and loss resulting from press-offs, the adverse effects on the product, and other undesirable features are incurred, and to provide a device for effecting such results, that shall be simple and durable in construction, economical to 15 manufacture and effective in its operation.

Another object is to control the needles of a flat knitting machine in a manner novel in relation to means for controlling or actuating them, 20 as by holding the needles inactive during selected revolutions of the cam shaft, preferably in the lowest cyclic position thereof, during predetermined revolutions of the cam shaft, and providing automatic means for selectively effecting 25 idle courses, during the fabrication of full-fashioned hosiery.

A further object of the invention is to provide a device, of the above-indicated character, with an auxiliary control unit, which, as in the prior 30 art, is controlled by a main pattern device, but, which, unlike such art, does not require a constantly operating power-transmitting means, or linkage, between the cam shaft and the unit, which is periodically rendered effective. Contrary to such operation which causes undue 35 vibration, wear and expense, the corresponding feature herein operates only when necessary, and simplifies the structure and operation to a material degree.

A still further object is, in combination with means for preventing the feeding of yarn to the needles during the travel of a carrier through an idle course to provide an auxiliary pattern unit that shall be more flexible in adjustment to 40 different patterns.

With these and other objects in view, which will become apparent from the following detailed description of the illustrative embodiment of the invention, shown in the accompanying drawings, 50 our invention resides in the novel mechanism and means for operating the same, as hereinafter more particularly pointed out in the claims.

In the drawings:

Figure 1 is a fragmentary plan view of a por- 55

tion of a full fashioned knitting machine embodying our invention;

Fig. 2 is a front elevational view of the structure shown in Fig. 1;

5 Fig. 3 is a vertical sectional view of one form of the invention;

Fig. 4 is a detail view of certain of the mechanism shown in Fig. 3;

Fig. 5 is a view similar to Fig. 3 of a modified 10 form of the invention;

Fig. 6 is a detail view of certain of the mechanism shown in Fig. 5; and

Fig. 7 is a diagram of the leg blank of a full fashioned stocking, together with pattern chains 15 for cooperation with the forms of the invention represented by Figs. 3 and 5, respectively, indicating the positions along the blank at which the steps occur in the sequence of operation of the idle course mechanism.

20 The figures illustrate parts of a Reading full fashioned knitting machine embodying the invention. For clearness, only those parts of the machine necessary to an understanding of the invention are illustrated; the other parts, and the 25 operation thereof being well known in the art, as shown and described in the "Reading" Full Fashioned Knitting Machine Catalogue, copyright 1929, and published by the Textile Machine Works, Reading, Pennsylvania.

30 Referring to the drawings, in a usual full fashioned knitting machine, upright frame members 12 are held in spaced relation to each other by transverse members including a front rail 14, a back rail 16, a front bed 17, and a center bed 18. 35 This structure supports the various other elements, or operating mechanism proper, completing a full fashioned knitting machine.

A cam shaft 19, rotatably and axially movable relative to its supporting bearings, which are carried 40 by the frames 12, carries a series of cam discs secured thereto, which separately cooperate with the various mechanisms to impart cyclic movements thereto. Axial shifting of the cam shaft 19, for positioning the cams to actuate the machine through either the narrowing or regular 45 knitting cycles, is effected, in a usual manner, by a main pattern device or chain mechanism C, which cooperates with shiftable cams 22, carried by the main cam shaft 19, in an order determined 50 by the positions of buttons carried by a pattern chain 23, see Fig. 1.

A plurality of friction boxes 24, only one of which is shown, see Fig. 3, are held in yielding engagement with a friction rod 26, and are connected 55 by slides 27, having handles 28, to a selected rod of a plurality of carrier rods 29, by being placed between dogs on these rods.

During the knitting operation, the yarn is fed, 60 by yarn carriers 31 on the rods 29, to sinkers 32 and dividers 33, for movement thereby between needles 34, which are held in a needle bar 36 by clamps 37. The initial forward movement of the sinkers is effected by reciprocating slur cock boxes 38, and intermediate jacks 39. Retraction 65 of the sinkers, and all movement of the dividers, are effected by a catch bar 42, which receives its movement from a cam 43, Fig. 5, through an intermediate linkage comprising a cam follower 44, a back catch lever 46, a back catch shaft 47, 70 a vertical shifting lever 48, and a horizontal lever 49.

The upward and downward movements of the needles are effected by a shaft 52, which is oscillated by a cam 53 through a lever 54, as shown in 75 Fig. 3, or a lever 54a, as shown in Fig. 5, and a

cam follower 56, which is held in engagement with the cam 53, by a spring 57. The shaft 52 operates the needles 34 through a lifting arm 58 carrying a pin 59, on which the needle bar 36 is pivotally mounted. During downward travel 5 of the needles, they are moved into engagement with the presser edge of a sinkerhead S to close the beards of the needles, and to hook the newly coulied loops beneath the beards, while the loops of the next previous course slide over the 10 beards, and are given off to the fabric. The forward and rearward travel of the needles is effected by a presser cam cooperating with a roller 62 rotatably carried by a presser lever 63, which is supported by a shaft 64, and connected to the 15 needle bar through a lever 66 and a fork 67.

Narrowing movements, distinctive from the ordinary knitting movements of the needles, are imparted thereto by cams which are positioned by shifting of the cam shaft to the right, whereupon a cam 68, instead of the regular knitting cam 53, coacts with the roller 62. The other mechanisms are similarly operated; a follower 69, rotatably mounted on a narrowing lever 72, and moving as determined by the contour of its narrowing cams, operating a narrowing mechanism N.

The usual idle-course mechanism comprises means, cooperating with the cam follower 62, for shifting the follower into alignment with a special cam, the contour of which prevents contact of the needles with the presser edge, during downward travel of the needles, to retain the loops of the next previous course beneath the beards, instead of casting these loops off to the 35 fabric, as is done during the usual knitting process.

The extra wear on the yarn, during the running of an idle course, caused by the retention of the loops between the sinkers and knockover bits 40 for a second needle-operating cycle, instead of the single-needle-operating cycle, effected during the knitting of a course, plus the entangling of the yarn with the needles, renders the above-mentioned prior art idle-course mechanism less 45 desirable, so far as its use in high-speed production, and in automatic machines is concerned.

In accordance with the invention, the needles are held inactive below the sinkers, during an otherwise complete cycle of the knitting machine, 50 thereby eliminating the wear ordinarily caused by the movement of the needles relative to the loops thereon, and preventing entanglement of the yarn with the needles.

In the form of the invention, of Figs. 1, 2, 3 and 55 4, a cam 73 is provided in the series of needle cams, the circular contour of which is such that, when engaged by an auxiliary roller 74 mounted on an extension of the usual cam follower axle 76, the needle lever will be maintained inoperative, 60 in substantially the same position as that effected by the above-described mechanism.

The operation of this mechanism is controlled by an auxiliary control unit E, including a chain 65 77 carried by, and moving with, an auxiliary shaft 78. The shaft 78 is intermittently rotated by means, associated with the cam 79, including a cam follower 82 rotatably mounted on a bell crank 83, the movements of which are imparted 70 to a pawl 84 through a carrying member 87 therefor, loosely mounted on the control shaft, and connected to the crank 83 by a link 85. The pawl 84 cooperates with a ratchet wheel 90 fixed to the shaft 78, which is prevented from reverse 75

rotation by a toothed lever 91 also cooperating with the ratchet wheel 90.

The bell crank 83 is normally held in inoperative or inactive position, relative to its operating cam, by engagement of a rest lever 86 with the free end of the crank 83. When a button 88, on a chain 89, of the main pattern device, actuates a lever 91 and in turn a lever 92, Fig. 2, and consequently, actuates the rest lever 86 linked thereto by an intermediate shifting rod 93, the lever 86 is positioned, as better seen in Figs. 1 and 2, whereupon the cam follower 82 will be permitted to follow the contour of the cam 79, which action intermittently turns the control shaft once during each revolution of the cam shaft, while the rest lever 86 is thus held in inoperative position.

A subsequent movement of the pattern chain moves the button 88 out of engagement with the lever 91, whereupon a spring 99, maintained under tension between the fixed bracket 94 and a collar 96 secured to the rod 93, operates to move the rod 93 to the right. Thus, the lever 86 is moved about its pivot 91, by collars 98 on the rod 93, into operative position beneath the arm of the bell crank, which is thus maintained inoperative, until a following movement of the pattern chain operatively positions another button under the lever 91, at which time the above-described procedure will be repeated.

High links 103 are spaced on the chain 77 to effect a selected sequence of operations of the idle course mechanism. When a high link engages a roller 104 of a lever 106, the latter, being pivotally mounted on a bracket 107 secured to the back rail 16, the lower portion of the lever 106 disengages a member 108, which releases a roller 109 for coaction with the periphery of a cam 112.

Simultaneously with the above described action, a roller 114 coacts with the inner face of the cam 112, whereupon a lever 116 moves a rod 117 to the right, as viewed in Figs. 1 and 2, through a member 118 secured to the rod 117, this action imparting a similar movement to a fork 119, whereby the roller 114 is aligned with the cam 112. Further rotation of the cam shaft causes the high portion of the cam 112 to engage the roller 109 to raise the forepart of the member 108, and consequently, lowers the rear portion thereof, permitting a spring 122 to draw the lever 106 into engagement with the member 108. Continued rotation of the cam shaft 19 moves a cam 123 into engagement with the roller 114, whereupon the roller 114 is again disposed in an inoperative position to thus render the idle course mechanism inoperative until another high link engages the roller 104.

A bracket 124, in which the member 108 is pivotally supported, is itself pivotally mounted in a bearing 126 of the bracket 107 which is supported by the back rail 16, thereby allowing vertical and horizontal movement of the roller-carrying lever 108. The connection between the fore end of the member 108 and the shifting rod 117 permits vertical movement of the member 108 relative to the roller shifting rod, whereas any lateral movement of the former will impart a corresponding movement to the idle course roller 114.

In a modified form of our invention, illustrated in Figs. 5 and 6, a member or lever 127 is pivotally supported by a stud 128, a supporting bracket 129 of which is secured to the front rail 14, as by a bolt 132, the lever 127 is nor-

mally disposed in inoperative position aside the path of a set screw 133 carried by the free end of the needle lever 54a. Placing of the rest lever 127 in operative position is effected by suitable levers similar to the levers 91 and 92 carried by the chain mechanism C, Figs. 1 and 2, through an intermediate rod 134, slidably supported by brackets 94, which are secured to the front rail 14, as illustrated in Fig. 6.

A compression spring 137, carried by the rod 134 between a collar 138 thereof and the bracket 94, normally positions the rod 134 to hold the lever 127 aside the path of movement of the set screw 133, which positions are normally maintained, until a button on the pattern chain 15 actuates the operating lever of the rod 134, by which action this rod will receive left hand movement to the position indicated in Fig. 6. This action imparts a clockwise movement to the lever 127, about the axis of the stud 128 through collars 139 carried by the shifting rod which contacts with the lower end of the lever 127 to move the latter to the position shown. This action engages the lever 127 to the free end of the needle lever 54a to latch the cam follower 56 25 in inoperative position preventing it from following the contour of cam 53, and to maintain the needles inactive in their lowermost position, substantially as illustrated in Fig. 5.

The movement of the rest lever 127 is effected 30 only when the cam follower 56 engages the high portion of its cam 53, in which position the needles are positioned below the sinker structure. A pad or shoulder portion of the lever 127 engages a regulating shaft 142 to prevent 35 bending of the lever from the pull of the spring 57 on the lever 54a. After a complete revolution of the cam shaft 19, an operative movement of the pattern chain advances the idle course button from engagement with its lever, 40 thereby leaving the spring 137 free to move the rod 134 to the right, as viewed in Fig. 6, which action imparts a counterclockwise movement to the lever 127, about the axis of the stud 128, 45 to inoperative position, and again permitting the spring 57 to act on the lever 54a to cause its roller 56 to follow the contour of its cam, whereupon, upward and downward movement of the needles is resumed.

The embodiment of the invention above described, consequently maintains the needles inoperative in their lowermost cyclic position, during a complete revolution of the cam shaft, and thereby, precludes movement of the needle relative to the loops. By reason of the position maintained by the needles, although a yarn carrier may be moved across the knitting field during an idle course, the yarn thereof will not become entangled with the needles, since no contact of the 50 yarn is made therewith.

As illustrated in Fig. 7, the sequence of operation of the idle-course mechanism is determined, in the form of the invention of Figs. 1, 2, 3 and 4, by the high link 103 of the auxiliary pattern unit chain 77. These high links of each pair control 65 the idle-course operation or position of the needles, when a carrier is moving through an idle course to the right, and the other high link of each pair controls the idle course operation or position of the needles, when a carrier is moving 70 through an idle course to the left.

The above sequence of operation of the needles during idle courses is similarly effected in connection with the modified form of the invention of Figs. 5 and 6, by pairs of buttons on the main 75

pattern chain, as indicated in broken lines to the right of the stocking blank in Fig. 7.

The stocking leg blank L extends from the top edge 146 of the folded welt portion W, to the course 147 of the heel tabs T, T. A line 148 indicates the first course of loops of the welt W in an open state.

Prior to knitting the first course of loops 148 of the welt W, the control chain 77 is operated 10 a distance corresponding to a distance relative to the blank from a line 149 to the course 148, and which controls the operation of the machine for two courses; i. e. during couloring from the right side of the knitting field to the left side, 15 to press the loops of course 147 of the heel tabs T from the needles, and back again. These movements are essential in order to reposition the various mechanisms of the machine.

The stocking is then knit to a course 152, where 20 a pair of high links 103 of the control chain 77 cause the machine to operate for two idle courses, or a distance extending from course 152 to course 153 inclusive. The first link of this pair operates to effect movement of the ravelling course carrier from right to left into an operative position, and the second link to effect movement of the couloring mechanism back to the right side of the machine to continue knitting. During the first 25 idle movement, all the carriers are held stationary, except the ravelling course carrier, and, during the second idle movement, all the carriers remain idle.

Knitting is continued to a course 154, where 30 the high links of another pair cause the machine to operate for two idle courses, or a distance extending from course 154 to a course 155. The first link of this pair controls the movement of the couloring mechanism from the right to the left side of the knitting field, during which movement the carriers remain idle. The second high link effects movement of carrier 2 to the inside splicing line coincident with the repositioning of the couloring mechanism to the right side of the machine.

45 Knitting is continued to a course 156 where another pair of high links 103 cause the needles to remain inoperative through two successive idle courses, or for a distance extending from course 156 to course 157. The first link of the pair causes 50 the needles to remain idle during a movement of the couloring mechanism from right to left, during which interval all the carriers remain idle; and the second link causes the needles to remain in their lowermost inoperative position during a 55 movement of the couloring mechanism from the left to the right side of the knitting sections, meanwhile the ravelling course carrier is removed from the knitting field.

60 Knitting is continued to a course 147 where another pair of high links 103 again control the operation of the machine for two idle courses, the first high link controlling the operation of the machine during movement of the couloring mechanism from right to left, while certain of the carriers are moved to their inoperative positions on the left side of the machine, and the second high link controlling operation of the machine during couloring from left to right, as 65 the remaining carriers are moved to their inoperative positions on the right side of the machine.

The main pattern chain controls the operation of the machine in substantially the same manner as the control chain 77, and carries double but- 70 ton 158, as diagrammatically illustrated in Fig. 7,

to control the positioning of the needles during the insertion of idle courses.

The structure illustrated in Figs. 1, 2, 3 and 4 embodies a single linkage including the link 85, between the auxiliary pattern unit E, at one end 5 of the linkage, and the cam shaft 19 and the main pattern device C at the other end of the linkage. This linkage not only transmits the driving force of the cam shaft to the auxiliary pattern unit, but is also effective in accordance 10 with the selection of the mechanism C to have this force applied only at preselected intervals. This operation is an improvement over the operation wherein one member or linkage is under constant operation between the cam shaft and 15 the control unit, and a separate linkage is provided for rendering the operating linkage periodically effective.

The improvements specifically shown and described, by which the above-mentioned results 20 are obtained, can be modified in various ways without departing from the spirit and scope of the invention as herein set forth and claimed.

We claim:

1. A knitting machine comprising knitting 25 mechanism including a bank of needles, a cam shaft, a cam on said shaft, a follower for said cam, means for shogging the shaft, means for feeding yarn to the needle mechanism including a carrier for traversing the needles, means for 30 moving the carrier through an idle course, and means for preventing the feeding of yarn to the needles during the travel of the carrier through said course, by shogging said follower relative to the cam independently of shogging the shaft, including an auxiliary pattern unit, a cam element on the shaft, linkage including a follower element for the cam element, said elements being movable relative to each other between operative and inoperative positions affecting the operation 40 of said unit, and means including a main pattern device for controlling said movement.

2. A knitting machine comprising knitting 45 mechanism including a bank of needles, a cam shaft, a cam on said shaft, a follower for said cam, means for shogging the shaft, means for feeding yarn to the needle mechanism including a carrier for traversing the needles, means for moving the carrier through an idle course, and means for preventing the feeding of yarn to the needles, 50 during the travel of the carrier through said course, by shogging said follower relative to the cam independently of shogging the shaft, including an auxiliary pattern unit embodying a variable-link chain, linkage between the shaft and 55 the unit for operating the unit, and a main pattern device for controlling the operation of the unit by the shaft.

3. A knitting machine comprising knitting 60 mechanism including needles, means for feeding yarn to said mechanism including a carrier for traversing the needles, means for moving the carrier through an idle course, and means for preventing the feeding of yarn to the needles during the travel of the carrier through the idle 65 course including a cam shaft, means including an auxiliary cam on the shaft and an auxiliary-cam follower, the cam and the follower being movable relative to each other between operative and inoperative positions, an auxiliary pattern unit for controlling said relative movement, a main cam on the shaft, linkage including a main-cam follower for effecting the operation of the auxiliary pattern unit, and means including a main pat- 70

75

tern device for controlling the operation of said linkage.

4. A knitting machine comprising knitting mechanism including needles, means for feeding yarn to said mechanism including a carrier for traversing the needles, means for moving the carrier through an idle course, and means for preventing the feeding of yarn to the needles during the travel of the carrier through the idle course including a cam shaft, means including a secondary cam on the shaft and a secondary-cam follower, means including a tertiary cam on the shaft and a tertiary-cam follower for controlling the operation of the secondary cam and its follower, an auxiliary pattern unit for controlling the tertiary cam and its follower, a primary cam on the shaft, and linkage including a primary-cam follower for affecting the operation of the auxiliary unit.

5. A knitting machine comprising knitting mechanism including needles, means for feeding yarn to said mechanism including a carrier for traversing the needles, means for moving the carrier through an idle course, and means for preventing the feeding of yarn to the needles during the travel of the carrier through the idle course including a cam shaft, means including a secondary cam on the shaft and a secondary-cam follower, means including a tertiary cam on the shaft and a tertiary-cam follower for holding the secondary-cam follower at a high point of the secondary cam and releasing it to follow the secondary cam, face-cam means for relatively shifting said tertiary cam and its follower axially between operative and inoperative positions for holding and releasing the secondary cam follower, cam means on the shaft for lifting the face cam follower out of range of the face-cam means and lowering the face-cam follower into said range, linkage between the main cam and the auxiliary control unit for controlling the lifting and lowering of the face-cam follower, and means including a main pattern device for controlling actuation of the auxiliary pattern unit by the main cam.

6. In a knitting machine, the combination with a cam shaft, a cam on the shaft, a cam follower, a knitting mechanism including a bank of needles, a yarn carrier for traversing the needles, a pattern device, and means for moving the carrier through an idle course, of means for preventing the feeding of yarn to the needles during the travel of the carrier through the idle course comprising a lever pivoted about an axis parallel to the cam shaft for supporting the follower, and having a latch portion, and a lever controlled by the pattern device for movement about an axis at right angles to said first axis and having a latch portion for cooperation with the latch portion of the follower-supporting lever to hold the follower at a high point of the cam and to release the follower to follow the contour of the cam.

7. In a knitting machine, the combination with a frame including a front beam, a cam shaft, a cam on the shaft, a cam follower, a knitting mechanism including a bank of needles, a yarn carrier for traversing the needles, a pattern device, and means for moving the carrier through an idle course, of means for preventing the feeding of yarn to the needles during the travel of the carrier through the idle course comprising a lever pivoted about an axis parallel to the cam shaft for supporting the follower and having a latch portion, and a lever mounted on the front beam for movement by the pattern device about an axis at right angles to said first axis and having a

latch portion for cooperation with the latch portion of the follower-supporting lever to hold the follower at a high point of the cam and to release the follower to follow the contour of the cam.

8. In a knitting machine, the combination with a cam shaft, a cam on the shaft, a cam follower, a knitting mechanism including needles and a needle bar, a yarn carrier for traversing the needles, a pattern device having thereon variably spaced contact points, and means for moving the carrier through an idle course, of means for preventing the feeding of yarn to the needles during the travel of the carrier through the idle course comprising means including a lever connecting the follower to the needle bar, and a lever controlled by the pattern device for movement between positions in one of which it holds said first lever to maintain the needles in lowered position during said idle course carrier travel, and in the other position of which it releases said first lever for operation by the cam.

9. In a full fashioned knitting machine, the combination with a frame including a front beam, a cam shaft, a cam on the shaft, a cam follower, a knitting mechanism including needles and a needle bar, a yarn carrier for traversing the needles, a pattern device, and means for moving the carrier through an idle course, of means for preventing the feeding of yarn to the needles during the travel of the carrier through the idle course comprising linkage connecting the follower to the needle bar, and a lever pivotally mounted on the front beam and controlled by the pattern device for holding said linkage to maintain the needle bar in lowered position during the travel of the carrier through the idle course, and for releasing the linkage to be operated by the cam.

10. In a multi-section straight knitting machine, a pattern chain and a longitudinally shiftable rod extending along the machine, a cam shaft, a cam on the shaft, a follower for the cam, a needle bank, means including a carrier for feeding yarn to the needles, means for effecting idle-course movement of the carrier, and means for holding the needles below the course-laying position during movement of the carrier through an idle course comprising linkage between the follower and the needles for effecting movement of the needles between upper and lower positions, means including a portion for controlling the operative relation of the follower to the cam, a lever for holding and releasing the control portion, and mechanism operating between the pattern chain and the shiftable rod for actuating the rod to control the lever.

11. In a multi-section straight knitting machine, a frame, a pattern device, a cam shaft, a cam on the shaft, a follower for the cam, a needle bank, means including a carrier for feeding yarn to the needles, means for effecting idle-course movement of the carrier, and means for holding the needles below the course-laying position during movement of the carrier through an idle course comprising linkage between the follower and the needles for effecting movement of the needles between upper and lower positions, means including a portion for controlling the operative relation of the follower to the cam, a double-arm lever pivotally mounted on the frame between the lever arms one of which is for holding and releasing the control portion, and mechanism operating between the pattern device and the other arm of the double-arm lever for controlling the lever.

12. A knitting machine comprising knitting mechanism including a bank of needles, a cam shaft, a cam on the cam shaft, a follower for the cam, means for shogging the shaft, means for feeding yarn to the needle mechanism including a carrier for traversing the needles, means for moving the carrier through an idle course, and means for preventing the feeding of yarn to the needles during the travel of the carrier through said course, by shogging said follower relative to the cam independently of shogging the shaft.
13. In a knitting machine, the combination with a cam shaft, a cam on the shaft, a cam follower, a knitting mechanism and a needle bar, a yarn carrier for traversing the needles, a main pattern device, an auxiliary pattern device, and means for moving the carrier through an idle course, of means for preventing the feeding of yarn to the needles during the travel of the carrier through the idle course comprising means including a lever connecting the follower to the needle bar, means controlled by said auxiliary pattern device including an element for movement between positions in one of which it holds said lever to maintain the needles in lowered position during said idle course carrier travel and in the other position of which it releases said lever for operation by the cam, and a lever controlled by said main pattern device for movement between positions in one of which it maintains said auxiliary pattern device inactive and in the other position of which it establishes a connection between the auxiliary pattern device and the cam shaft for operation of the auxiliary pattern device by the cam shaft.
14. In a straight knitting machine, a needle bar, a cam shaft, means for moving the needle bar including a cam on the camshaft and a follower for said cam, a main pattern mechanism, means for shogging the camshaft, an auxiliary pattern mechanism, connections from said auxiliary pattern mechanism to said follower for shogging said follower with reference to its cam independently of the shogging of the camshaft, means for driving the auxiliary pattern mechanism including a cam on the camshaft and a follower therefor, and means operated by said main pattern mechanism for controlling the drive for said auxiliary pattern mechanism.
15. In a straight knitting machine, a needle bar, a camshaft, means for shogging the cam shaft, means for moving the needle bar including a cam on the camshaft and a follower for said cam, a main pattern mechanism, means for moving the needle bar for knitting, and means for producing an idle course motion of the needles including, in addition to said camshaft and main pattern mechanism, an auxiliary pattern mechanism, connections from said auxiliary pattern mechanism to said follower for shogging said follower with reference to its cam independently of the shogging of the camshaft, means for driving the auxiliary pattern mechanism including a cam on the camshaft and a follower therefor, and means operated by said main pattern mechanism for controlling the drive for said auxiliary pattern mechanism.

MELCHIOR ZWICKY.
